Inventor:

C. C. Bomberger

UNITED STATES PATENT OFFICE.

C. C. BOMBERGER, OF WEST CARLISLE, OHIO.

METHOD OF ELEVATING WATER.

Specification of Letters Patent No. 25,879, dated October 25, 1859.

To all whom it may concern:

Be it known that I, C. C. BOMBERGER, of West Carlisle, in the county of Coshocton and State of Ohio, have invented a new and 5 useful hydraulic device for elevating water and communicating a force thereto for the conveyance of the same to certain points or for the propulsion of machinery; and I do hereby declare that the following is a 10 full, clear, and exact description of the same, reference being had to the annexed drawing, making a part of this specification, said drawing being a vertical central section of my invention.

15 To enable those skilled in the art to fully understand and construct my invention I will proceed to describe it.

A, represents a bent tube or pipe the lower end of which extends down into the 20 well or reservoir B, from which the water is to be raised the lower end of said pipe having a valve α , within it opening upward. The upper end of tube A, extends down within an air-tight box C, nearly to 25 its bottom, the end of A, being open. From the lower part of the box C, a bent tube D, projects. The lower part of this tube is horizontal and is provided at its end with a valve α , opening upward. The lower part 30 of the tube D, is within an open vessel E, which is above an air-tight box F, the two air-tight boxes C, F, communicating with each other at their upper parts by means of a pipe G.

35 H, is a tube within the box F. The upper end of this tube H, communicates with the open vessel E, and the lower end is provided with a valve b, opening upward. The stem of the valve b, is attached to a lever I, 40 having its fulcrum at c. The outer end of lever I, is bent upward and it has a float J, attached to it.

K, L, are two bent levers having their fulcra at d, e, provided respectively with floats 45 M, N, at their upper ends and having slide bolts f, g, attached at or near their lower ends, said bolts serving to lock the lever I, in its two different positions. This will be more fully explained hereafter. To the lever I, the stem r, of a valve O, is attached. This valve O, is in the upper part of the 50 discharge pipe P, which communicates with the lower part of the box F.

Q, is a small pipe which communicates 55 with the upper part of the pipe P, and the lower part of box F.

The operation is as follows: The box F, is filled or nearly filled through tube H with water and when full or nearly full the float M, is buoyed up so that the lever K, will 60 draw back the bolt f. The float J, will also be actuated or buoyed up so that the lever I, will close the valve b, at the bottom of tube H, as soon as the bolt f is withdrawn the valve O, will open as b closes, the lever I, 65 being retained in its latter position by bolt g, which was actuated by the float N, as the water rose in F. When the valve O, is opened the water in F, will pass through the pipe Q, and down pipe P, and as the water 70 in F, descends the space above it will be filled with air from box C, through pipe G. The displacement of the air in C, will of course cause the water in the well B, to raise valve α , and pass up pipe A, and fill box 75 C. When the box F, is empty the float N, will by its own gravity actuate the lever L, and bolt g, the latter releasing the lever I, so that it may by its own gravity and that of its float raise the valve b, and close valve 80 O, the lever K, also being moved so that its bolt f, will pass under the lever I, and retain the valve in an open state. When the valve b is open, water passes down the tube H, from the open vessel E, which is supplied from C, and the air in F, as F, fills with water is forced back into C, said air forcing the water from C, into E. When the vessel F, is again filled the floats M, J, 85 N, are consecutively actuated by the water 90 owing to their buoyancy, the valve b, closed and O, opened so that the water will escape down P, as before.

The discharge pipe P, it will be seen extends below the well or reservoir B, and consequently the principle of the siphon is included in the invention. But by having the siphon parted and connected by the air-tight boxes C, F, and pipe G, I am enabled to obtain what may be termed a "head" in F, 100 and the water will be discharged from P, with a force due to its height from the lower end of P, to the level in F, whereas if an ordinary siphon were employed, the water would be discharged from P, with a force 105 due only to the excess of the length of the longer leg over the shorter one.

By using two devices and having the water discharged alternately a continuous stream may be discharged, with one device the water 110 is discharged intermittently.

I do not confine myself to the precise ar-

angement of parts or means employed for actuating the valves *b*, *O*. It is necessary of course that said valves be operated automatically and floats may be connected to 5 levers and arranged in various ways to effect the purpose, but the within described means would probably be as good as any.

It will be understood that the pipe *A*, is 10 of such height that the water may be forced into *C*, by atmospheric pressure, but the device may be used in wells deeper than 33 feet by placing box *C*, in the well within 33 feet from the water and having a column of water above box *F*, of sufficient height to 15 balance the column in the well above *C*.

Having thus described my invention what I claim as new and desire to secure by Letters Patent, is,

The arrangement of the air-tight boxes *C*, *F*, connected by the pipe *G*, and communicating respectively with the pipes *A*, *P*, 20 in connection with the open vessel *E*, tube *H*, and the valves *b*, *O*, placed in the tube *H*, and pipe *P*, and operated automatically 25 as shown, or in an equivalent way for the purpose set forth.

C. C. BOMBERGER.
